UNITED STATES PATENT OFFICE.

BENJAMIN SILVERMAN, OF CHATTANOOGA, TENNESSEE, ASSIGNOR OF ONE-HALF TO
J. RUSSEL EARP, OF CHATTANOOGA, TENNESSEE.

COMB.

Application filed November 7, 1923. Serial No. 673,257.

To all whom it may concern:

Be it known that I, BENJAMIN SILVERMAN, citizen of the United States, residing at Chattanooga, in the county of Hamilton and State of Tennessee, have invented certain new and useful Improvements in Combs, of which the following is a specification.

This invention relates to hair dressing and has special reference to a device for straightening wavy or kinky hair.

More particularly the invention relates to an improved hair straightening comb.

One important object of the invention is to improve the general construction of devices of this character.

A second important object of the invention is to provide a comb of this character having separate metallic teeth secured in a position in an improved and novel manner.

A third important object of the invention is to provide a novel assembly arrangement for such a comb wherein a single bolt or pin is used to hold all of the parts together.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a comb constructed in accordance with this invention.

Figure 2 is a vertical longitudinal section through such a comb.

Figure 3 is a section on the line 3—3 of Figure 1.

Figure 4 is a section on the line 4—4 of Figure 1.

Figure 5 is a disassembled view showing a slight modification of certain parts of the device.

The comb as herein shown comprises a back 10 having socket openings 11 at each end and provided on its under side with a channel 12. At each end of the back is provided an end plate or tooth 13 having

a projecting pin 14 fitting in the respective sockets 11. These pins may either be made integrally with the teeth 13 or may be simply engageable in recesses 15 as shown in Figure 5. In each of the end teeth 13 is also provided a shank receiving opening 16.

In connection with this back a series of teeth 17 are provided which have their base or butt portions fitted in the channel 12 and are kept in properly spaced relation by spacers 18 similarly fitted in said channel. These teeth and spacers are provided with openings registering with the openings 16 so that a rod or shank 19 may be slipped through said openings and hold the parts together. On one end of this rod is provided a head 20 which bears against the outer surface of one of the end teeth while the other end carries a tubular washer 21 bearing against the other end tooth. A handle 22 is fitted on the projecting end of the shank and a nut 23 is used to draw all the parts together and bind them in their assembled relation as clearly seen in Figure 2.

In use the device is first heated to the desired degree. It is then grasped by the handle, which is preferably of wood or the like, and the hair is combed until the kinks or waves are straightened out, the heating operation being repeated from time to time as may be found necessary.

There has thus been provided a simple and efficient device of the kind described and for the purpose specified.

Having thus described the invention, what is claimed as new, is:

1. In a comb of the class described, a back, end teeth having pin and socket interlocking engagement with the ends of the back, alternate intermediate and separate teeth and spacers between said end teeth, a headed pin passing through the end and intermediate teeth and spacers and having its headed end resting on one of the end teeth, and means carried by the other end of the pin for clamping the parts together.

2. In a comb of the class described, a back having a socket at each end and provided with a channel in its under side, end teeth each carrying a pin engaging in its respec-

tive socket, alternate intermediate teeth and spacers having base portions fitted in said channel, a pin passing through the end and intermediate teeth and the spacers and projecting at one end, a head on the remaining end of the pin bearing against one end tooth, a tubular washer on the projecting end of

the pin bearing against the remaining end tooth, a handle on said projecting end engaging the washer, and a nut at the butt end of the handle screwed on the pin to bind the parts together. 10

In testimony whereof I affix my signature.

BENJAMIN SILVERMAN.
